UNITED STATES PATENT OFFICE.

SAMUEL S. STOLP, OF MANSFIELD, OHIO, ASSIGNOR TO THE OHIO BRASS COMPANY,
OF MANSFIELD, OHIO, A CORPORATION OF NEW JERSEY.

ELECTRICALLY-OPERATED TRACK SWITCH.

Application filed December 12, 1923. Serial No. 680,151.

To all whom it may concern:

Be it known that I, SAMUEL S. STOLP, a citizen of the United States of America, residing at Mansfield, in the county of Rich-
5 land and State of Ohio, have invented cer-
tain new and useful Improvements in an
Electrically-Operated Track Switch, of
which the following is a specification.

My invention relates to track switches and
10 particularly to that class of track switches
which is electrically operated by the opera-
tor of a moving vehicle.

The object of my invention is to provide
15 an automatic electrically operated track
switch system which works "power on" and
"power off" the motors to operate the switch
in the desired direction and provided with
means which will prevent the burning out
20 of the operating coils if current is applied
to the system beyond a predetermined time.

My invention resides in the new and novel
combination and relation of circuits, sole-
noids and electrically operated switches and
25 other parts more fully hereinafter described
and shown in the drawings.

In the drawings accompanying my speci-
fication:

Fig. 1 is a schematic drawing to be used
in describing the so-called "power on" and
30 "power off" operation of the switch.

Fig. 2 is a schematic drawing of my in-
vention showing the relation of the parts in
a normal condition.

Fig. 3 is a schematic drawing of my in-
35 vention showing the relation of the parts
after current has been supplied to the sys-
tem for a predetermined time with "power
off" the motors.

Fig. 4 is a schematic drawing showing
40 the relation of parts immediately after the
current has been supplied to the system with
"power on" the motors.

Referring to Fig. 1, I have shown certain
45 car circuits and parts which effect the op-
eration of the system which has a current
collector or trolley wheel W, a trolley pole
T by means of which the current collector
is mounted upon the car or moving vehicle
50 and C represents a controller for opening
and closing a circuit to the car motors M,
the controller being operated by the opera-
tor. There are various auxiliary devices up-
on a car, as a rule, which receive current,
such as heaters H, lights L and air compres-

sor F, all circuits having a connection to 55
the ground G.

The motors M are under the control of
the car operator, but the current flowing
through the parts H, L and F is not under
the control of the operator through the op-
eration of the controller C. The current 60
flowing through the parts H, L and F may
amount to considerable and must therefore
be taken into consideration in the design of
various parts hereinafter described. The 65
current flowing through the motors M is
very large and this fact is made use of in
the operation of my invention such that
when this current is flowing through the
motors due to the controller being closed 70
and which I will term the "power on" pos-
ition, and if the collector W is in engage-
ment with a contact pan P, the switch
tongue will be thrown to one position, usu-
ally the "curve" position, and if no current 75
is flowing through the motors M due to the
controller being open, and which position
I will term the "power off" position, and
the collector W is in engagement with the
pan P the switch tongue will be thrown in 80
the opposite direction, which I will term the
"straight ahead" position.

Referring to Fig. 2, I mount upon the
trolley conductor 1 a contact pan P provided
with two contact members 2 and 3 which are
parallel to each other, but insulated from
each other except when engaged by the col-
lector W. The contact members 2 and 3 are
so arranged that when the collector W en-
gages the pan P the collector is out of en-
gagement with the trolley conductor 1. 90
When the collector engages the pan P, the
contact members 2 and 3 are electrically con-
nected and if the controller is set to the
"power on" position current will be free to 95
flow from the conductor 2 through the col-
lector W, pole T, controller C, and motors
M to ground, but if the conductor is set
to the "power off" position the contact mem-
bers 2 and 3 will be electrically connected, 100
but no current will flow from the contact
member 2 through the motors M to ground,
but current may flow through the parts H, L
and F to ground. I employ a track switch
S which is provided with a switch tongue 4 105
operable to the "straight ahead" or "curve"
position. The switch is also provided with
two solenoids 5 and 6 for operating the

switch tongue. The solenoids are provided with a reciprocating plunger 7 which is drawn inwardly by the solenoid 5 and drawn outwardly by the solenoid 6. The 5 solenoid 5 might be termed the "power off" solenoid as it is energized only when the collector engages the pan P with "power off" and the solenoid 6 might be termed the "power on" solenoid as it is energized only 10 when the collector engages the pan with "power on" the motors. One end of each solenoid is connected to the ground through the common conductor 8 and the plunger 7 is connected to the switch tongue 4 by the 15 rod 9.

I also employ a switch A, which I will term a selector switch, for the reason that its function is to position its armature with respect to the conductors leading to the solenoids 5 and 6 for proper directional operation 20 of the tongue 4. The switch A is provided with a coil 10, usually of large wire and low resistance and few turns. All current for operating the system must flow 25 through this coil and also the current for operating the motors when the collector engages the pan with "power on." At the same time the coil 10 must be so proportioned that when the collector engages the 30 pan P with "power off" the current flowing through the auxiliary car circuits will not operate the armature 11. The arm 11 is normally held downward by gravity or a spring, and is raised only when the coil 10 is sufficiently 35 energized with "power on." One terminal of the coil 10 is connected to the trolley conductor 1 by the conductor 12 and the other terminal is connected to the contact member 2 by the conductor 13. The switch arm 11 is connected to the contact member 3 by the conductor 14. The arm 11 engages the contacts 15 and 16. From the contact 15 a circuit leads to the remaining terminal of the solenoid 5 through the 40 conductors 28 and 17, switch arm 18 and its contact 19. A circuit leads from the contact 16 to the remaining terminal of the solenoid 6 through the conductors 20, 21 and 30, switch arm 22, contact 23 and holding 45 coil 31. The arms 18 and 22 normally maintain the circuits to the solenoids 5 and 6 closed. The arms are connected together by means 24 and the arms will operate to open and close substantially simultaneously. 50 The means 24 may be a bar of insulating material or it may be a spring insulated from the members 18 and 22 so as not to electrically connect them, or other suitable means. To control the arms 18 and 22 I employ a solenoid 25 which has one terminal connected to the arm 11 through the conductor 26 and has the other terminal connected to the trolley conductor 1 through the conductor 27. The coil 25 is preferably composed of a large number of turns and high

resistance to permit only a small flow of current. The coil 25, its armatures and other parts I will term the switch B. The coil 25 maintains the armatures 18 and 22 normally closed, but permits the armatures to open 70 the circuits which they control after a pre-determined time after the collector has engaged the pan P. This action is brought about by the de-energization of the coil 25 through the fact that one terminal of the coil 25 75 is connected to the trolley conductor and the other terminal is likewise connected to the trolley conductor when the contact members 2 and 3 are bridged by the current collector and after de-energization the arms 80 18-22 drop by gravity. Therefore, we have the trolley connected to both terminals of the coil 25 when the collector engages the pan P and, therefore, no current can flow 85 through the coil 25 and the armatures will be released.

As I desire the operating current to flow 90 through the solenoids 5 and 6 for a sufficient time to energize them I provide the switch B with a time lag which may consist of a copper or brass sleeve 32 which may also surround the coil B, or adjust the relation of the armature 22 with respect to the core of the coil B in the way of clearance, or I may use a combination of the two or other means well known to the trade for effecting 95 a time lag in the dropping of the armature 22. It will be noted that under normal conditions the coil 25 receives its energizing 100 current from the trolley conductor 1 through the conductor 27 and that the other terminal is connected to the switch arm 11 and that from the switch arm 11 a circuit leads to the ground through the solenoid 5 and this provides a ground whereby the circuit is completed 105 normally through the solenoid 25, but when the switch arm 18 is open the connection to the ground is broken and the coil 25 cannot again be energized to pick the arm 22 up and hold it in a closed position unless some 110 means is provided for doing this. Therefore, from the ground side of the coil 25 I connect a high resistance R which leads to the conductor 30 and this resistance provides 115 a ground for the coil 25 through the solenoid 6. It will now be seen that if the ground connection of the coil 25, through the switch arm 18, is broken that the current can then flow from the trolley conductor 1 120 through the coil 25, the resistance R, the conductor 30, etc. to ground, thereby energizing the coil 25 and picking the armatures up. It is evident that the combined resistance of the coil 25 and R must not be so great as to prevent a sufficient current flowing 125 through the coil 25 when the arm 18 is open so that the ampere turns of the coil 25 will not be sufficient to energize the coil so as to attract the arm 22. At the same time the resistance of the coil 25 and the re- 130

sistance R should be sufficient to cut the current flowing therethrough to a low value which is not sufficient to effect in any way the operation of the solenoids 5 and 6. The 5 current which is normally flowing through the coil 25 and resistance R, the latter being small as it is practically short circuited by the circuit through solenoid 5 when the switch B is closed, and likewise through 10 the solenoids 5 and 6 will tend to warm the solenoids 5 and 6 and thereby prevent ice forming about the same in the winter time as these solenoids are placed in a box in the ground and subject to the action of water 15 and the formation of ice within this box is liable to interfere with the operation of the tongue 4. At the same time the current flowing through the coil 25 and resistance R, which together with the switch A, are 20 mounted in a control box which is usually mounted on a pole, will sufficiently warm the parts within the control box to prevent the formation of moisture therein.

In place of using the resistance R as 25 shown in Figs. 2 and 3, it may be placed in shunt with the switch arm 19 as designated by R' in Fig. 4. In this case it will be evident that when the switch B is open and the switch A has its armature in engagement 30 with the contact 15 which would be the position of these parts after the collector has engaged the pan and passed off of it providing the engagement of the collector with the pan is equal to or greater than the time 35 lag of the switch B, that the resistance R' will complete the ground connection for the coil 25 and the same will then be energized and pick up the arms 18 and 22 thereby restoring the system to normal. It is also 40 evident that when restored to normal the resistance R' will be short circuited and practically no current will flow therethrough.

When the car operator desires to go 45 "straight ahead" he will do so by setting his controller to "power off" and coast over the pan P. As soon as he engages the pan P current will flow through the solenoid 5 by way of the conductors 14, 28 and 17, the contacts 15 and 19 and the switch arms 11 and 50 18 thereby energizing the coil 5 and moving the tongue 4 to the position shown in Fig. 3. If he engages the pan P longer than a predetermined time, as for instance, if he should 55 for some reason stop with the collector in engagement with the pan, the short circuiting of the coil 25, as already explained, will permit the arms 18 and 22 to drop and thereby open both branch circuits and prevent the burning out of the solenoid 5 (see Fig. 60 3). When the operator starts the car it will be necessary for him to throw the controller to the "power on" position and this will cause the coil 10 of the switch A to be sufficiently energized to move the arm 11 into 65 engagement with the contact 16, but as the

switch B is open no current can flow through the coil 31 and hence the switch will not be changed from the position intended. If the operator intends to take the curve he will throw his controller to "power on" position 70 when engaging the contact pan with the collector, and this will immediately energize the coil 10 of the switch A and move the arm 11 into engagement with the contact 16 and current will then flow through the solenoid 6 thereby energizing this solenoid and moving the switch tongue to the "curve" position, all parts taking the position shown in Fig. 4. If for any reason he should stop 75 with his collector in engagement with the pan P, the switch B will operate as heretofore explained, and open the circuits thereby preventing the switch tongue being moved to the wrong position.

If the operator should pass over the pan at 80 a very high rate of speed with "power on" and should not engage the pan for the predetermined time, the coil 31 will be energized as long as current is flowing through the solenoid 6 and will continue to flow until 85 the switch B opens as predetermined, the coil 31 be energized and the arm 11 drop. The coil 31 also prevents a false operation 90 of the system if the operator intentionally engages the pan with "power on" and before 95 leaving the pan should turn his controller to "power off," as under such operation the arm would immediately drop and throw the switch tongue to the "power off" position were it not for the coil 31. 100

There are modifications and re-arrangements of the circuit which may be made to the system herein disclosed, but which will still produce systems within the scope of my invention and therefore, I do not wish to be 105 limited other than by my claims.

I claim:

1. A switch operating system comprising in combination a trolley conductor, a pan P having two contact members to be engaged 110 by a current collector, an electrically operated track switch S adapted to be moved to a predetermined position when the collector engages the pan with "power on" or "power off," a selector switch for controlling the positioning of the track switch by connecting one or the other of two branch circuits to the track switch, a circuit connecting one contact member with the selector switch, an operating coil 10 for the switch A connected to 115 the trolley conductor and to the other contact member and adapted to be energized sufficiently to operate the switch A with "power on" only, a switch B controlling the branch circuits and holding the branch circuits normally closed and operating to open the same after a predetermined time after the collector engages the pan and to remain open while the collector engages the pan, an operating coil 25 for the switch B adapted to 120

be normally energized, but to be de-energized when the collector engages the pan, means operating to re-establish the energization of the coil 25 after the collector leaves the pan and a holding coil 31 to maintain the switch A in its "power on" position until the switch B has opened.

2. A switch operating system comprising in combination, a trolley conductor, a pan P having two contact members to be engaged by a current collector, an electrically operated track switch S adapted to be moved to a predetermined position when the collector engages the pan with "power on" or "power off," a selector switch for controlling the positioning of the track switch by connecting one or the other of two branch circuits of a power circuit to the track switch, a circuit connecting one contact member with the selector switch, an operating coil 10 for the switch A connected to the trolley conductor and to the other contact member and adapted to be energized sufficiently to operate the switch A with "power on" only, a switch B controlling the individual branch circuits and positioned therein and holding the branch circuits normally closed and operating to open the same after a predetermined time after the collector engages the pan and to remain open while the collector engages the pan, an operating coil 25 for the switch B adapted to be normally energized to hold the switch B closed, but to be de-energized when and remain de-energized while the collector engages the pan and means operating to re-energize the coil upon the collector leaving the pan to reclose the switch B.

3. A switch operating system comprising in combination, a trolley conductor, a pan P having two contact members to be engaged by a current collector, an electrically operated track switch S adapted to be moved to a predetermined position when the collector engages the pan with "power on" or "power off," a selector switch for controlling the positioning of the track switch by connecting one or the other of two branch circuits of a power circuit to the track switch, a circuit connecting one contact member with the selector switch, an operating coil 10 for the switch A connected to the trolley conductor and to the other contact member and adapted to be energized sufficiently to operate the switch A with "power on" only, a switch B controlling the individual branch circuits and positioned therein and holding the branch circuits normally closed and operating to open the same after a predetermined time after the collector engages the pan and to remain open while the collector engages the pan, an operating coil 25 for the switch B adapted to be normally energized to hold the switch B closed, but to be de-energized when and remain de-energized while the collector engages the pan by short

circuiting the coil 25 to open and maintain open the switch B and means to re-establish the energization of the coil 25 upon the collector leaving the pan to re-close the switch.

4. A switch operating system comprising a trolley conductor, a pair of contact members to be engaged by a current collector, one contact member being connected to the trolley conductor, an electrically operated track switch, a branched circuit leading from the other contact member to the track switch and electrically operated means positioned in the branches of the branched circuit to normally close the branch circuits and means to deenergize the electrically operated means after the collector has engaged the contact members for a predetermined time and means to establish an auxiliary ground for the electrically operated means to re-energize the same while the branch circuits are open.

5. A switch operating system comprising in combination, a trolley conductor, a pair of contact members to be engaged by a current collector, an electrically operated track switch to be automatically moved to its operable positions, means for controlling the direction of movement of the track switch, a divided circuit connecting the source of power, the said means and the track switch, and an electrically operated switch positioned in the branch circuits to control each of the branch circuits leading to the track switch to open or close the branch circuits simultaneously, the operating mechanism of the electrically operated switch being connected to the conductor and to one of the contact members and means comprising a high resistance circuit to temporarily re-energize the operating mechanism to re-close the electrically operated switch.

6. A switch operating system comprising in combination, a trolley conductor, an electrically operated track switch, a branched circuit to the track switch, current controlling means operated automatically from a car to control said circuit for transmitting current from the conductor to the track switch to operate it in the desired direction, and electrically operated means operated automatically by the current collector to first open the branch circuits by the collector short circuiting the electrically operated means and to later close them when the short circuit is removed.

7. In a switch operating system the combination of, a trolley conductor, a pan to be engaged by a current collector, an electrically operated track switch, a branched circuit leading to the track switch, a selector switch to control the branched circuit, switches in the branches to open and close same, an operating coil to control the switches, one coil terminal deriving current from the conductor and the other terminal having a cir-

cuit leading to the ground to close the switch and maintain it closed, the said circuit opened by one of the switches in the branch circuits when the collector engages the pan.

8. In a switch operating system the combination of, a trolley conductor, a pan to be engaged by a current collector, an electrically operated track switch, a branched circuit leading to the track switch, a selector switch to control the branched circuit, switches in the branches to open and close same, an operating coil to control the switches, one coil terminal deriving current from the conductor and the other terminal having a circuit leading to the ground and opened by one of the switches in the branch circuits when the collector engages the pan and means connected to the last said coil terminal and 20 to the ground to cooperate with the coil to close said opened switch.

9. In a mechanism of the class described, the combination of an electrically operated track switch, a trolley conductor, a contact pan to be engaged by a current collector, a branched circuit deriving current from the conductor and leading to the track switch and an electrically operated switch to control the opening and the closing of the 25 branch circuits and electrical means to control the opening and closing of the last said switch comprising a coil to be short circuited by the current collector to de-energize the coil and thereby to open the switch and 30 a grounded circuit including a resistance external to the coil and connected thereto to re-establish the energization of the coil to close the switch.

10. In a switch operating system the combination of, a trolley conductor, a contact pan to be engaged by a current collector, an electrically operated track switch, electrically operated means to control the positioning of the track switch, circuits connecting the aforesaid elements such that the system works "power on" or "power off" the motors to position the track switch as desired, means to prevent the burning out of the track switch operating means if the collector 45 stands too long in engagement with the pan comprising a normally closed switch to control the circuits leading to the track switch and arranged to open after a predetermined time and remain open while the collector 50 engages the pan and means adapted to re-establish the normal closed position of the said normally closed switch comprising a resistance across the terminals of the normally closed switch and which becomes operative when the switch is open and the collector 55 is out of engagement with the pan.

11. In a switch operating system the combination of, a trolley conductor, a pan connected to the trolley conductor, a selector

switch having a switch arm, a conductor 65 connecting the switch arm to the pan and to be connected to the trolley conductor by a current collector, a track switch mechanism, circuits to the track switch and separately energized by the switch arm, means 70 to position the switch arm at will of a car operator, a switch having switch arms controlling each of the circuits to the track switch to place each circuit in an open or closed condition simultaneously, means controlled by the collector engaging the pan to open the last said switch after a predetermined time if the collector still engages the pan and means to close the said switch after the collector leaves the pan. 75

12. A switch system comprising a conductor, a pair of contact members to be engaged by a current collector, one contact member being connected to the trolley conductor, an electrically operated track switch, 80 a circuit leading from the other contact member to the track switch, a switch arm normally closing the said circuit, electrically controlled means to operate the switch arm and having a coil deriving current from the trolley conductor and arranged to be short circuited by the collector engaging the contact member to open the switch arm, a circuit connecting the coil with the trolley conductor and the ground and opened and closed by the switch arm and means comprising a high resistance circuit connecting the coil to ground to re-establish the circuit through the coil to close the switch arm after the collector leaves the contact 95 members. 100

13. A switch operating system comprising in combination, a trolley conductor, an electrically operated track switch, a branched circuit to the track switch, circuit controlling means operated automatically from a car to control said circuit for transmitting current from the conductor to the track switch to operate it in the desired direction and electrically operated means 105 operated automatically to first open the branch circuits and to later close them, the electrically operated means comprising switch arms and a coil to operate the same to closed position when energized, the coil connected to the trolley conductor and to ground and said connection opened and closed by the switch arm, the coil arranged to be short circuited by the collector engaging the contact members to deprive the coil of current and a high resistance path in parallel with the switch arm to re-establish the energization of the coil when the collector leaves the contact member and the switch arms are open in order to close the switch 110 115 120 125 arms and return the system to normal.

In testimony whereof I affix my signature.
SAMUEL S. STOLP.
